UNITED STATES PATENT OFFICE

LEOPOLD KAHL, OF BERLIN-DAHLEM, GERMANY

DISCONTINUOUS DISTILLATION OF TARS

Application filed November 26, 1923, Serial No. 677,187, and in Germany December 20, 1922.

The present invention refers to the distillation of tars, especially coal-tars but also other tars and has the object, to obtain the final distillates, ready for the market, directly from the tars.

Hitherto the process generally used has consisted in distilling the coal tars to obtain four fractions (the so called raw fractions) (1) the light oil, passing over up to 10 150 degrees centigrade, (2) the middle oil, boiling between 150 and 200 degrees centigrade, (3) the heavy oil, boiling between 200 and 310 degrees centigrade, (4) the anthracene oil or green oil, boiling between 300 15 and 400 degrees centigrade, the residue in the retort constituting the pitch. Each of the four fractions was then subjected to careful fractional distillation, a suitable fractionating column being employed in order to effect complete separation. By this 20 fractional distillation several products were obtained, as raw benzol, carbolic oil, crude naphthalene, washing oils, motor fuel oils, impregnating oils, anthracene oils, crude 25 anthracene etc., which were either directly sold or from which certain products as cresols, phenols, pyridine, pure naphthalene, acenaphthene, anthracene, carbazol were manufactured. Tars of the other sources, 30 as from brown coal were also separated into several raw fractions which were then further fractionated. This process had the disadvantage, that it was necessary to first prepare raw fractions by condensation and then 35 subject these to one or more fractional distillation which process is expensive because of the large consumption of fuel, in the separate stills etc. By the separation of the tars into raw fractions the several chemically 40 quite different substances, as phenols, bases, hydrocarbons etc. went into the various fractions and not into a single raw fraction, which rendered their preparation in a pure state very difficult and caused losses.

45 The present process consists in that the

tar is gradually vapourized so destructive distillation is as far as possible obviated and the vapours are directly and immediately fractionated or dephlegmated, the condensed portions or fractions being returned to the 50 tars which are being distilled. The vapours from the tar are in my process conducted directly and without previous condensation into a highly efficient dephlegmating or fractionating column and are here gradually and 55 fractionally condensed, the substances of different boiling points being separated from each other as completely as possible. This is effected by forcing the vapours through separate chambers placed above each other and connected by pipes for the passage of the 60 vapours and having pipes for the return flow of the condensed liquid, a certain portion of the vapours being condensed in each chamber, the vapours being forced to go 65 through the liquid in each respective chamber. The separation of the substances according to their different boiling points is effected by cooling the vapours and forcing 70 the vapours through the fractionally condensed liquids so gradually that it is possible to secure fractions of sharp boiling points as required for the market. This is effected practically by arranging the column 75 with a certain number of fractionating or dephlegmating chambers and conducting the distillation and cooling so that the desired separation according to the boiling point occurs. The vapours are led into a device 80 which is essentially a dephlegmator or fractionating column having a series of perforated plates provided with overflow tubes. Such an apparatus per se is well known and is made in many different forms. The less volatile constituents of the vapours are successively cooled or condensed in the successive chambers, the more volatile constituents 85 passing upwardly and the condensed liquids passing downwardly into the distillation still.

In the drawing I diagrammatically show three forms of apparatus suitable for carrying out my method. In Fig. 1 the still 1 is heated by means of a heater 2 and communicates with the dephlegmator or fractionating column 5 at the top of which I provide the inclined pipe 3 which communicates with the cooling device or condenser 4. The horizontal plates 6 divide the column into several successive chambers. Each plate 6 has a vertical pipe 7 provided with a dome 8, and it also has one or more overflow pipes 9 to fix the height of the liquid layer therein. The ascending vapours are caused to bubble through the layers of liquid on each plate 6 since the bottom of each dome 8 is below the layer of liquid on its respective plate 6.

Fig. 2 shows a modification of the well known form of dephlegmator or fractionating column above mentioned in which the well known Raschig rings are provided.

Fig. 3 shows another form of dephlegmator in which horizontally arranged sieves are provided in the dephlegmator column 12. The openings in these sieves are so fine that while the vapours can bubble through them, the condensed layers of liquid do not flow backward until they have reached a certain height upon each of the said sieves.

The operation of the device shown in Fig. 1, for example, is as follows:—

The tar in the still 1 is first heated to the temperature at which the first fraction can pass into the outlet tube 3. A certain amount of the constituents having higher boiling points are vapourized and these are successively condensed on the plates 6 so that the bottom plate 6 has the largest amount of constituents of high boiling point condensed thereon. Hence, the vapours passing into the condenser 4 represent the refined product or fraction having the lowest boiling point. After the passage of the first fraction through the condenser 4 has stopped, the temperature to which the contents of the still 1 is heated is increased to the boiling point of the second desired fraction, and this temperature is maintained until no more vapour is evolved. While the second purified fraction is being condensed, more of the constituents having higher boiling points are deposited in the form of liquid layers upon the plates 6. In this manner, the volatile constituents of the tar are separated with a minimum consumption of fuel into sharply defined fractions having the desirable properties above mentioned.

Whereas the phenols, cresols and xylenols in the usual distillation of coal tar enter into all fractions, according to the present invention the said compounds are sharply confined to the carbolic oil or naphthalene oil fraction.

The carbolic oil and the washing-oil fraction obtained according to the present process are free from naphthalene. The latter is only found in the naphthalene fraction of narrow boiling points. The crude naphthalene obtained therefrom has the quality of a redistilled product of the old process. One obtain 50% more of naphthalene from the tar than according to the present process.

Practically the whole quantity of phenol, cresols and pyridine are in the carbolic oil and in the naphthalene oil fraction. The oil drained off from the naphthalene fraction can be used immediately for the manufacture of carbolic acid without redistillation. After the naphthalene fraction distillates go over which are sharply distinguished from the naphthalene fraction and allow an acenaphthene to crystallize of 94% purity and higher which is after mechanical separation from the oil suitable for the market. The following fraction allows fluorene of 70% purity to crystallize, which will be converted into pure fluorene by a single crystallization, whereas hitherto fluorene could be obtained from coal tar only by complicated and expensive chemical processes. Here after one obtains the anthracene fraction sharply distinguished by its clearing point (the point of temperature at which the mixture becomes a thoroughly clear liquid) the solid substances therein containing anthracene and carbazol in the proportion of about 14:2 and give after simple crystallization from benzol hydrocarbons an anthracene of about 90% purity. Associated with this is chiefly phenanthrene, which remains as residue from the distilled hydrocarbons and is a crude phenanthrene with about above 75% purity. It may be purified by crystallization from alcohol. Finally one obtains a carbazol fraction giving after solidification a solid mixture of about 17 parts carbazol and 25 parts anthracene, from which the carbazol may be separated by dissolving the mixture in hydrocarbons and may be purified by crystallization from organic bases, mixtures of bases and hydrocarbons or by means of the potash melting process.

Distilled tar has already been continuously distilled by conducting the vapours of single raw fractions, for instance those from the light oil fraction or from the middle oil fraction into separated fractionating columns. The purpose of the use of the fractionating columns in the said known process is to divide the raw distillates from the various stills into two fractions. In the known processes, there is no return of the reflux condensates from the column into the retort. In the present process however the vapours leaving the tar distilling still are conducted immediately and

directly, without being divided or separated into raw fractions, into a very efficient fractionating column in which they are fractionated. By this proceeding I obtain the new and surprising result of preventing the various compounds from the tars being condensed in all fractions. They are sharply separated in individual fractions and one obtains a prompt and immediate sharp separation from each other.

10 The present process may be applied for distilling tars of all sorts and kinds, not only to coal tars, but also to tars from brown coal, shale etc. The fractions from brown coal tar according to the present process are for instance crude solar oil, benzene, paraffine oils, paraffine mass, fat oils.

15 The present process is carried out by distilling the raw tar from an ordinary distillation still into a highly efficient fractionating column. If raw coal tar is distilled in an ordinary distillation still having arranged directly on the top thereof a bell column with about 40 chambers or a sieve column of the same effect or a column filled with so called 20 Raschig rings the following products are obtained:

	Per cent
Carbolic oil	3.25
30 Naphthalene fraction	18.9
Washing oil	8.1
Anthracene oil	14.75
Pitch	54.0

35 By crystallization of the naphthalene and draining off the oil carbolic oil 6.5%, is obtained as well as 15.6% of naphthalene suitable for direct pressing, the yield of the other products being the above quoted. On the 40 other hand there is obtained by distillation from the still, the same as in the above quoted example, but without immediate fractionating of the vapours and therefore without use of a fractionating column the following 45 results:

	Per cent
Water	0.3
Crude light oil	0.2
Crude middle oil	12.7
50 Crude heavy oil	10.3
Pitch	52.2
Loss	0.6

55 The constituents of the raw fractions obtained without fractionating of the vapours and without the use of a fractionating column are—

	Light oil	Middle oil	Heavy oil	Anthracene oil
Specific gravity at 15 degrees centigrade	0.992	1.022	1.048	1.106
Water	1.0%	0.5%	Traces.	Traces.
Acids	12.0%	18.0%	8%	6%
Bases	4.0%	6.0%	5%	6%

The process of the boiling of the several fractions was the following:

Beginning	85°	150°	207°	250°	70
	Per cent	Per cent	Per cent	Per cent	
-150°	12				
-160°	17

-312°				90	

Solidifying point of the pitch 59 degrees centigrade. 120

Whereas in the ordinary distillation by first condensing the vapours from the still no fractionating is obtained and the several fractions are present in each distillate, the present invention gives a sharp separation of the several fractions which are sharply distinguished from each other, the fractions boiling within very narrow limits. The intervals of the boiling points in each fraction are in the 125 130

products of the invention no more than 20 degrees centigrade, whereas the intervals in the ordinary distillates are 60 to 100 degrees centigrade. In the products of the present invention the separation of the naphthalene and of the acids is especially remarkable.

A further improvement in the process consists in that I distill the raw tar according to the above described process with immediate 10 fractional separation of the vapours and the fractions condensed are chosen so that I obtain after the carbolic oil fraction, fractions containing chiefly the various solid hydrocarbons which fractions are further divided 15 by crystallization. These crystals are separated from the liquid constituents, whereupon the solid thus obtained hydrocarbons are vapourized gradually in a still, the temperature being gradually increased and the vapours 20 are immediately and directly fractionated while constantly reconducting the reflux condensation products into the tar in the still subjected to distillation. The fractionating column of the first distillation is arranged to 25 obtain substantially a naphthalene fraction having boiling points between 190 to 220 degrees centigrade, afterwards an acenaphthene fraction having a boiling point of about 240 to 280 degrees centigrade, then a fluorene fraction having a boiling point of about 275 to 30 295 degrees centigrade, then a phenanthrene fraction having a boiling point of about 290 to 345 degrees centigrade, and finally an anthracene fraction of a boiling point of about 315 to 350 degrees centigrade. The said fractions are separated and cooled to ordinary 35 temperature or below, until the solid hydrocarbons are separated, a certain portion of each fraction remaining fluid. The said 40 liquid oils are separated mechanically from the solid hydrocarbons, for instance by allowing them to drop off from the crystals or by centrifuging the mixture. The said solid hydrocarbons are then brought to a still and 45 gradually vaporized, the vapours being directly and immediately fractionated or dephlegmated in a highly efficient fractionating column as described above for the raw tars. The vapours are led immediately and directly 50 to a highly efficient fractionating column, so the vapours are condensed gradually and progressively, so that the rising vapours go through the condensates formed and the condensates are returning to the distilling still.

55 The raw naphthalene separated from the naphthalene fraction alluded to is heated in a distilling column gradually to 210-218 degrees centigrade and the vapours are directly and immediately subjected to a highly efficient fractionating. I obtain a first fraction 60 of a boiling point of about 180 to 210 degrees centigrade and a distillate or fraction solidifying at cooling to about ordinary temperature, having a melting point about 78.5 to 79 65 degrees centigrade, resembling in its proper-

ties nearly completely to the commercial pressed crude naphthalene, manufactured hitherto by pressing in heated presses and draining off the liquid, a very tedious and expensive operation.

The yield of the present process calculated on the same weight of raw naphthalene is higher than in the hitherto common method.

The crude acenaphthene fraction is cooled and the crude acenaphthene solidified after 75 cooling to ordinary temperature or below is separated from the oily portions. The said crude is vaporized gradually in a still by heating to 270 to 280 degrees centigrade and the vapours fractionated immediately and directly. I obtain an acenaphthene of about 80 99% purity.

The solid fluorene separated from the fluorene fraction is vapourized gradually by heating in a still to about 285 to 295 degrees centigrade. The vapours are led immediately and directly to a highly efficient fractionating column, where an immediate and direct efficient fractionating is effected. I obtain nearly pure fluorene and as second fraction afterwards condensed from the vapours diphenylendioxide of high percentage.

The solid hydrocarbons from the phenanthrene fraction, separated from the liquid portions of the fraction, are vapourized by 95 heating in a still to about 320 to 335 degrees centigrade. The vapours are immediately and directly led to a highly efficient fractionating column and here directly and immediately subjected to a highly efficient fractionating.

I obtain a phenanthrene of about 90% 100 purity and even higher, especially free of anthracene and carbazol, which may be freed from by constituents by crystallization from hydrocarbons, especially aromatic.

The crude anthracene, obtained from the anthracene fraction alluded to above after 110 cooling and mechanical separation from the oily constituents is vapourized by heating gradually in a still and the vapours are led immediately and directly into a highly efficient fractionating column, where immediately and directly an efficient fractionating is effected. I obtain a very pure anthracene 115 which may be crystallized from benzolhydrocarbons or a mixture of benzolhydrocarbons and aromatic bases, as aniline or, and its homologues, or pyridine or, and its homologues.

The other fractions which may be obtained besides crude anthracene as its residues from the distillation may be treated in the same manner as hereinbefore described by vapourizing and immediate and direct efficient fractionating. I obtain a fluoranthene fraction of the melting point from 70 to 80 degrees centigrade and boiling point 350 to 375 degrees centigrade which gives after cooling 125 crude fluoranthene containing 40% and more 130

fluoranthene. The second fraction is a pyrene fraction of the boiling point of 380 to 410 degrees centigrade, giving by cooling solids, consisting of about 50% pyrene. For obtaining 5 fluoranthene and pyrene from the solid one may extract it with carbon disulphide, whereby fluoranthene and pyrene are dissolved.

The process may be carried out at ordinary 10 atmospheric or diminished pressure.

I claim:—

1. The process for obtaining solid hydrocarbons from raw coal tar containing them consisting in evaporating those parts of the 15 raw coal tar which distill below the boiling point of the lowest boiling solid hydrocarbon contained in the raw coal tar and then heating the said tar gradually to substantially the boiling point of the solid hydrocarbon of the 20 lowest boiling point to generate its vapours, fractionating the vapours immediately, effecting a gradual condensing and revaporizing of the vapours so often that the vapours essentially contain the entire quantity of the 25 respective lowest boiling solid hydrocarbon contained in the said tar, reconducting continuously the total reflux from the fractionating operation into the said raw tar to be distilled, leading away the vapours containing 30 essentially one single solid hydrocarbon cooling the said vapours separating the solid hydrocarbon from the constituents remained liquid in the cooling process, heating the separated solid hydrocarbon, fractionating again 35 the vapours effecting a gradual condensing and revaporizing of the vapours reconducting continuously the total reflux from the fractionating operation into the said raw tar to be distilled, leading away the vapours and 40 cooling the said vapours.

2. The process for obtaining phenanthrene of high purity from raw coal tar containing it, which consists in treating the tar according to claim 1, and after having led away the 45 vapours boiling between 275-295 degrees centigrade heating the said tar further to generate vapours boiling between 290-345 degrees centigrade fractionating said vapours, effecting a gradual condensing and revaporizing 50 of the vapours so often that they contain all phenanthrene present in the raw coal tar reconducting continuously the total reflux from the fractionating operation into the raw coal tar to be distilled leading away the 55 vapours essentially containing all phenanthrene, cooling the said vapours to solidify the phenanthrene, separating the phenanthrene from the liquid constituents, heating the separated phenanthrene to about 320-335 degrees centigrade, fractionating the 60 said vapours immediately effecting a gradual condensing and revaporizing of the vapours, reconducting continuously the total reflux 65 from the fractionating operation into the raw

coal tar to be distilled leading away the uncondensed vapours and cooling the said vapours.

3. The process of discontinuous distillation of crude coal tar which comprises heating 70 the crude coal tar to vaporize therefrom a fraction, and intensively fractionating the vapors evolved in order to obtain this fraction in vapor form of largely homogeneous chemical character having a narrow boiling 75 point range.

4. A process as set forth in claim 3 in which liquid is formed during the fractionating operation and is returned to the tar undergoing treatment.

5. The process of discontinuous distillation 80 of crude coal tar which comprises heating the crude coal tar to vaporize at least a fraction thereof, and intensively fractionating the vapors evolved in order to obtain this fraction in vapor form of largely homogeneous chemical character having a narrow boiling point range and returning any liquid 85 formed during the fractionating operation to the tar undergoing heat treatment.

6. A process as set forth in claim 3 in which the temperature of the crude coal tar is intermittently raised to obtain a series of fractions of successively increasing boiling point, the fractions being intensively fractionated 95 to obtain the series of fractions of largely homogeneous chemical character having a narrow boiling point range.

7. A process as set forth in claim 3 in which the temperature of the crude coal tar is raised 100 in order to obtain a series of fractions of successively increasing boiling point, the boiling point increment being not greater than approximately 20° C.

8. A process as set forth in claim 3 in which the temperature of the crude coal tar is intermittently raised in order to obtain a series of fractions of successively increasing boiling point, the fractions being subjected to intensive fractionation to obtain them of largely 110 homogeneous chemical character having a narrow boiling point range, the separated fractions containing substantial proportions of normally solid hydrocarbons.

9. The process of discontinuous distillation 115 of crude coal tar which comprises heating the said tar to vaporize at least a portion thereof and intensively fractionating the evolved vapors, raising the distillation temperature of the crude coal tar to vaporize 120 portions of successively increasing boiling points and fractionating the evolved vapors in order to separate from the crude coal tar a naphthalene fraction, an acenaphthene fraction, a fluorene fraction, a phenanthrene fraction, an anthracene fraction, a fluoranthene fraction and a pyrene fraction of largely 125 homogeneous chemical character having a narrow boiling point range.

10. The process of discontinuous distilla- 130

tion of crude coal tar which comprises heating the said tar to vaporize at least a portion thereof and intensively fractionating the evolved vapors, raising the distillation temperature of the crude coal tar to vaporize portions of successively increasing boiling points and fractionating the evolved vapors in order to separate from the crude coal tar a naphthalene fraction, an acenaphthene fraction, a fluoren fraction, a phenanthrene fraction, an anthracene fraction, a fluoranthene fraction and a pyrene fraction each of such fractions being of largely homogeneous chemical character having a narrow boiling point range, separately heating each such fraction to vaporize at least a portion thereof, fractionating the vapors evolved in order to obtain therefrom a fraction of narrower boiling point range than that of the fraction from which it was derived.

11. The process of discontinuous distillation of crude coal tar which comprises heating the said tar to vaporize at least a portion thereof and intensively fractionating the evolved vapors, raising the distillation temperature of the crude coal tar to vaporize portions of successively increasing boiling points and fractionating the evolved vapors in order to separate from the crude coal tar fractions having the following boiling point ranges: 190-220° C., 240-280° C., 275-295° C., a phenanthrene fraction, 315-350° C., a fluoranthene fraction, and a pyrene fraction.

In testimony whereof I hereunto affix my
35 signature.
